UNITED STATES PATENT OFFICE.

ROBERT NORDENSWAN, OF NEW YORK, N. Y., ASSIGNOR TO WESTERN ELECTRIC COMPANY, INCORPORATED, OF NEW YORK, N. Y., A CORPORATION OF NEW YORK.

VIBRATION-RESPONSIVE DEVICE.

1,330,491.

Specification of Letters Patent. Patented Feb. 10, 1920.

Application filed August 2, 1917. Serial No. 184,059.

To all whom it may concern:

Be it known that I, ROBERT NORDENSWAN, a subject of the King of Sweden, residing at New York, in the county of New York 5 and State of New York, have invented certain new and useful Improvements in Vibration-Responsive Devices, of which the following is a full, clear, concise, and exact description.

10 This invention relates to vibration responsive devices, and more especially to telephone receivers wherein the natural frequency of the diaphragm can be varied over a considerable range.

15 The principal object of the invention is to provide a vibration responsive device in which the natural frequency of the diaphragm can be quickly and easily tuned or adjusted over a wide range of frequencies, 20 and to this end, the diaphragm is held in fixed position and a member adjustable relatively thereto is provided to vary the effective area of the diaphragm and may also serve to further increase the range by 25 varying the stress therein.

Referring to the drawing which illustrates one embodiment of the invention, Figure 1 is a plan view of a telephone receiver with the cap and diaphragm thereof 30 removed; Fig. 2 a vertical cross-section thereof on the line 2—2 of Fig. 1; and Fig. 3 a view showing the application of a scale thereto to facilitate rapid adjustment.

The receiver has an exterior threaded 35 shell 1 of suitable non-magnetic material, the upper end 2 of which is of reduced diameter and extends partially across the shell 1 to provide an internal shoulder to which a magnet 3 is secured by screws 4.

40 L-shaped pole pieces 5 and 6 are secured to opposite ends, respectively, of the magnet 3 at the lower side thereof, while a circular plate 7 of non-magnetic material serves to partition off the forward end of the shell 1, 45 to form a magnet chamber and also aids to support the pole pieces 5 and 6 firmly in place. The screws 4 extending through the plate, pole pieces and magnet serve to hold these parts securely within the shell.

50 The lower end of the shell 1 is closed by a cap 8 having a central perforation 9 there-through for the passage of the usual con-

ducting cord to the receiver, and is secured against movement by a set screw 10.

The plate 7 carries a hook 11 to which a strain relief strand of the conducting cord may be secured, and also carries three binding posts 12, 13 and 14; the post 12 being in electrical contact with the plate 7 to admit of grounding the receiver if desired; while the posts 13 and 14 are insulated from both sides of the plate 7 by insulation 15 and have pins 16 and 17 extending into the magnet chamber. Electromagnetic receiver coils 18 and 19 connected in series are mounted 60 on the pole pieces 5 and 6, respectively, and each have one end of their windings connected to the respective pins 16 and 17.

An outer cylindrical shell 20 is threaded 70 for adjustment on the shell 1 and has an internal shoulder 21 which engages with a shoulder 22 on the shell 1 to limit the inward movement while a locking ring 23 may be used to lock the shells 1 and 20 in any desired relative adjustment. Spanner openings 24 may be provided if desired to facilitate movement of the shell 20 relative to the ring 23. The upper end of the shell 20 is of reduced diameter and exteriorly 75 threaded to carry a receiver cap 25 which is 80 screwed thereon, and serves to clamp a magnetic diaphragm 26 firmly thereto.

The upper end 2 of the shell 1 has a narrow non-resilient annular extension 27 85 designed to engage the diaphragm 26 to reduce the effective area thereof, when it is desired to tune the receiver to respond to higher frequencies than those to which the normal area of the diaphragm is responsive; the normal position being as shown in Fig. 90

2. The extension 27 can be made of various diameters relative to but less than the actual diameter of the diaphragm depending upon the particular range of frequencies to which it was desired to have the receiver responsive. If desired, one or more other adjustable members each having an annular extension similar to the extension 27 and adjustable relatively thereto, so that any desired extension can be brought into engagement with the diaphragm to limit the effective area thereof to that best suited for the purpose in hand, may be provided.

One such member 28 is shown in its

lowermost position on Fig. 2 of the drawing, in which position, the top of the diaphragm engaging the extension 29 is sufficiently below the top of the extension 27 so as not to interfere with the vibration of the diaphragm when the extension 27 is engaged therewith. In the uppermost position of the member 28, the extension 29 extends sufficiently above extension 27 so that the latter will not interfere with the diaphragm.

The member 28 is adjustable in the upper end 2 of the shell 1 and in its lowermost position abuts the magnet 3 while a shoulder 30 on the end 2 limits its upward movement to position the extension 29 for operative engagement with the diaphragm 27. Any suitable means may be used to normally hold the member 28 in its upper and lower positions; a spring pin 31 and recesses 32 being shown for this purpose, while spanner grooves 33 may be provided on the member 28 to facilitate movement thereof.

In addition to varying the effective area of the diaphragm, the annular extension 27 or 29 may be used to stress or bow the diaphragm and to vary the stress therein to more perfectly tune it to any desired frequency. In order to prevent too great a stress being placed on the diaphragm and giving it a permanent set, the shoulders 21 and 22, and the member 28 and shoulder 30, respectively are arranged to engage and limit further movement before the pressure between the extension 27 or 29 respectively and the diaphragm becomes sufficiently great to injure the latter.

When the effective area of the diaphragm is reduced as previously explained, it is preferable that the annular portion beyond the effective area thereof vibrate as little as possible and to overcome this an annular washer 34 of felt or other suitable material may be arranged between the receiver cap 25 and diaphragm 26 to overlie at least part of the non-effective area. As shown it overlies all the non-effective area when the extension 27 is used, and serves as a damping means to non-effective portions of the diaphragm when either the extension 27 or 29 is engaged therewith. The washer 34 is of such thickness that it will not normally exert sufficient pressure on the diaphragm to affect its natural period of vibration, nor appreciably affect its amplitude of movement, but on the diaphragm being stressed or bowed by the pressure of the extension 27 or 29, the washer is sufficiently compressed to effectually dampen the non-effective portion of the diaphragm.

The receiver construction shown can be satisfactorily employed with voice currents within the usual frequency range, by properly adjusting the air gap between the pole pieces and diaphragm, and without engag-

ing either of the extensions therewith; but for higher ranges of frequency, it is necessary for efficient operation to engage the extension 27 or 29 with the diaphragm to reduce the effective area thereof and to produce the degree of stress therein best suited to the desired frequency.

It is often desirable to quickly duplicate an adjustment which has been previously found by experiment to be satisfactory. To facilitate this, a portion of the thread on the shell 1 is removed as shown in Fig. 3 and a longitudinal scale 35 placed on the shell to indicate the position of the locking ring 23, while a scale 36 is arranged circumferentially of the shell 20 to admit of a micrometer adjustment thereof; an index line 37 being provided on the cover 8 for this purpose. In this way, the best position for each of the variety of conditions encountered would be determined experimentally and the reading of the scale noted for future reference and when it was desired to use the receiver again under like conditions, the parts would be directly adjusted to this position without further experiment by duplicating the scale position of the parts as previously determined.

What is claimed is:

1. In a vibration responsive device, a vibratory diaphragm, supporting means therefor for clamping said diaphragm substantially at the periphery thereof, and means to vary the effective vibratory area of said diaphragm to tune it to respond to a desired frequency.

2. In a vibration responsive device, a vibratory diaphragm, supporting means therefor for clamping said diaphragm substantially at the periphery thereof, and means to vary the effective area and the stress in said diaphragm to tune it to respond to a desired frequency.

3. In a vibration responsive device, a vibratory diaphragm, supporting means therefor, means to vary the effective area of said diaphragm to tune it to respond to a certain frequency, and means to dampen the vibration of the diaphragm within such areas as may be rendered non-effective by said area varying means.

4. In a vibration responsive device, a vibratory diaphragm, means to support said diaphragm, means to engage with and vary the normal effective area of said diaphragm to tune it to respond to a desired frequency, and means to dampen the vibration of the diaphragm within such areas as may be rendered non-effective by said area varying means; said damping means being operative only when the normal effective area of said diaphragm is changed.

5. In a vibration responsive device, a vibratory diaphragm, supporting means therefor, means at one side of said dia-

- phragm to vary the effective area thereof, and means at the other side of said diaphragm to dampen the vibration thereof within such areas as may be rendered non-effective by said area varying means. 5
6. In a vibration responsive device, a vibratory diaphragm, supporting means therefor, means at one side of said diaphragm to engage with and vary the normal effective area thereof to tune it to respond to a desired frequency, and means on the other side of said diaphragm to dampen the vibration thereof within such areas as may be rendered non-effective by said area 10
- 15 varying means; said damping means being operative only when said area varying means is engaged with the diaphragm.
7. In a vibration responsive device, a vibratory diaphragm, supporting means therefor clamping said diaphragm substantially at the periphery thereof, and a non-resilient member adjustable relative to said diaphragm to vary the effective vibratory area thereof to tune it to respond to a desired frequency. 20
8. In a vibration responsive device, a vibratory diaphragm, supporting means therefor, and a member having a non-resilient annular portion adjustable into and out 25
- 30 of engagement with said diaphragm to vary the effective area thereof to tune said diaphragm to respond to different desired frequencies.
9. In a vibration responsive device, a vibratory diaphragm, supporting means therefor, and means movable into and out of engagement with said diaphragm to provide a plurality of effective vibratory areas for said diaphragm different from the normal effective area thereof to tune said diaphragm to respond to different desired frequencies. 35
10. In a telephone receiver, a vibratory diaphragm, supporting means therefor, means having a portion adjustable relative to said supporting means movable into and out of engagement with said diaphragm to vary the effective area thereof to tune said diaphragm to respond to different desired frequencies, and a receiver magnet adjustable with said area varying means. 40
11. In a telephone receiver, a vibratory diaphragm, supporting means therefor, a magnet casing adjustable relative to said 45
- 50 diaphragm, an electromagnet having a pole piece within said casing, and an annular flange associated with said casing and adjustable to engage said diaphragm to reduce the effective area thereof; said magnet being mounted to maintain the pole piece 60 thereof a fixed distance below the top edge of said flange.
12. In a vibration responsive device, a vibratory diaphragm, supporting means therefor, a member adjustable relative to 65
- 70 said diaphragm to engage with and change the effective area from the normal effective area thereof, and a second member adjustable relative to said first member to engage with said diaphragm to provide an effective 70 area different from that provided by said first member.
13. In a vibration responsive device, a vibratory diaphragm, supporting means therefor, a member adjustable relative to 75
- 80 said diaphragm having an annular portion to engage with and change the effective area from the normal effective area thereof, and a second member carried by and adjustable relatively to said first member and having an annular portion to engage said diaphragm to provide an effective area different from that provided by said first member.
14. In a vibration responsive device, a vibratory diaphragm, supporting means therefor, a member adjustable relative to 85
- 90 said diaphragm having an annular portion to engage with and change the effective area thereof, a second member having an annular portion, and a member adjustable relative to said first member to position said annular portion above the annular portion of said first member whereby either of said members may be adjusted to engage said 95 diaphragm.
15. In a vibration responsive device, a vibratory diaphragm, supporting means therefor, a member adjustable relative to 100
- 105 said diaphragm having an annular portion to engage with and to change the effective area of said diaphragm, and a second member secured to said first member having an annular portion thereon; said second member being operable to adjust said portion above and below the annular portion of said first member whereby either of said members may be adjusted to engage said diaphragm.

In witness whereof, I hereunto subscribe my name this 1st day of August, A. D. 1917.

ROBERT NORDENSWAN.
